(57) **CLAIM**

The ornamental design for a cleaning pad, as shown and
described.

DESCRIPTION

FIG. 1 is a perspective view of a cleaning pad showing our
new design;

FIG. 2 is a top view thereof;

FIG. 3 is a side view thereof;

FIG. 4 is another side view thereof;

FIG. 5 is a front view thereof;

FIG. 6 is a rear view thereof;

FIG. 7 is a bottom view thereof;

FIG. 8 is another embodiment of a cleaning pad;

FIG. 9 is a top view thereof;

FIG. 10 is a side view thereof;

FIG. 11 is another side view thereof;

FIG. 12 is a front view thereof;

FIG. 13 is a rear view thereof; and,

FIG. 14 is a bottom view thereof.

The broken lines shown in the drawings are for illustrative
purposes only and form no part of the claimed design. The
dark stippled region shown in the drawings represent one or
more stripe of contrasting color, relative to the remaining
surface.

1 Claim, 4 Drawing Sheets
